UNITED STATES PATENT OFFICE

CHARLES T. COE, OF NEW YORK, N. Y.

GRATE.

SPECIFICATION forming part of Letters Patent No. 700,618, dated May 20, 1902.

Application filed August 9, 1901. Serial No. 71,424. (No model.)

To all whom it may concern:

Be it known that I, CHARLES T. COE, a citizen of the United States, and a resident of New York, in the county of New York and State of New York, have made and invented 5 certain new and useful Improvements in Grates, of which the following is a specification.

My invention relates to an improvement in 10 furnace-grates, the object of the same being to provide a device of this character which shall be cheap to construct, strong and durable in use, and which may be effectively shaken.

15 A further object of the invention is to so construct and arrange the parts that the several sections may be easily and readily removed and others substituted when necessary, either by reason of the burning out of 20 said sections or when desired to adapt the same for burning a different size of coal—that is, either from a larger to a smaller size, or vice versa.

25 A further object of my invention is to so construct and arrange the several parts of the grate that the least obstruction possible will be offered to the draft or current of air passing through the same and also that in the operation of shaking a chopping motion will be 30 effected, whereby the clinkers will be broken up or reduced in size to facilitate their passage through and out of the grate and also whereby the under or burned-out portions of the fire-bed may be removed or separated 35 from the upper or bright portions of the bed without necessarily disturbing the latter.

With these and other ends in view my invention consists in certain novel features of construction and combinations of parts, as 40 will be hereinafter fully described, and pointed out in the claims.

In the accompanying drawings, Figure 1 is 45 a plan view of my improved grate, one portion of the same showing the sections provided with plain elongated slots or openings and the remaining sections with slots and staggered openings, several of the sections being removed from one of the rocking frames. Fig. 2 is a sectional view taken on 50 the line 2 2 of Fig. 1, the rear portion of the grate being shown in its tilted position. Fig. 3 is a sectional view taken through one of the

sections and part of the rocking frame. Fig. 4 is a perspective view of one of the rocking frames, the sections being removed therefrom. Fig. 5 is a similar view of one of the leaves or sections.

Referring to the drawings, A represents the frame or support for the grate and is built in the usual way on the inside of the furnace-wall, (not shown,) the front and rear ends *a* of the frame being preferably toothed or serrated, as shown, to assist the free circulation of air through the grate. In the side pieces of the frame A are supported the transverse 65 rocking frames B, each constructed as illustrated in Fig. 4, for receiving and supporting the leaves or sections C. The rocking frames each consist of the two parallel supporting-bars *b c*, on which rest the edges of the leaves 70 or sections C, as illustrated in Fig. 2. With these supporting-bars are cast integral the division-plates *d*, extending slightly above said bars and slightly rounded or curved on their upper edges to conform to the shape of the face 75 or upper side of the leaves or sections C, the end plates *e f* being provided with a lug or projection *g* to act as bearings or supports for the rocking frame and adapted to fit into recesses formed in the sides of the frame A. 80 Running parallel with the supporting-bars *b c* and connecting the division-plates *d* and end plates *e f* is the strengthening flange or plate *h*, this plate or web having its greatest depth or width at about the center of its 85 length in order that it may impart to the rocking frame the greatest strength where such is needed—that is, about midway between the ends thereof—and thereby overcome any and all danger of sagging due to the weight im- 90 posed upon it. This rocking frame, constructed and arranged as above described, is preferably cast in one piece, and, as will be seen by reference to the drawings, is of such shape and design that it offers but little or 95 no obstruction to the free circulation of the air or draft through it, the bars and plates presenting their edges and not their sides to the flow or current of the air. Upon this rocking frame and between the division-plates *d* are supported the leaves or sections C, each leaf or section being cast in one piece and consisting of the parallel plates *i*, having openings or spaces between them and joined to-

gether by the ribs *k*, the openings providing for the passage of the air, the end plates *i* each having a lug or projection *l*, adapted to fit into recesses *m*, formed in the division-
 5 plates *d* of the rocking frame, to assist in supporting said leaves or sections in place within said rocking frame. It will be noticed that the upper edges or faces of the plates *i* of which the leaves or sections are formed are
 10 slightly thickened or broadened to impart a sufficient amount of strength thereto and to prevent the smaller sizes of coal from falling through between them, these upper edges of the plates being left plain or provided with
 15 staggered openings or recesses *n* to provide a greater space or vent for the air passing through the grate. By thus constructing the rocking frames and leaves or sections it will be understood that the latter may be easily
 20 and readily removed in case it becomes necessary to substitute a new section for one burned out or in the case where it is desired to change or adapt the grate to burn a larger or smaller size of coal. Further, it will be
 25 seen that the edges of the plates forming both the rocking frames and leaves present their edges in the direction of the flow or current of air, and thereby offer but little obstruction thereto. It will be further noticed by
 30 reference to the drawings that the lugs or projections *g*, formed on or secured to the end plates *e f* of the rocking frame, are located to one side of the center of said plates, the effect being to give to the forward edges of
 35 the leaves a slightly-greater movement than the rear edges, the result being that the forward edge of one leaf or section will, in conjunction with the rear edge of the adjacent section, operate to better crush the clinkers
 40 and separate the lower portion of the fire-bed from the upper portion than in the case where both the forward and rear edges move to the same extent, which latter would be the case were the rocking frames hung or pivoted at
 45 the center of their ends.

In order to effect a proper shaking of the grate, the end plates *e* of the rocking frames are continued downwardly to form vertical arms *o*, the extreme lower ends of which are
 50 provided with the lugs or projections *p*, to which latter are secured the rods *D*, which in turn are secured to the connecting-rods *E*.

The forward ends of these rods *E* are secured to the lower ends of the levers *F*, fulcrumed at *f'* to the plate *g'*, the latter being secured 55 to the front plate or wall *h'*, this arrangement of the parts allowing the forward and rear portions of the grate to be shaken separately or simultaneously.

Having fully described my invention, what 60 I claim as new, and desire to secure by Letters Patent, is—

1. In a grate, the combination with a supporting-frame, of rocking frames mounted in said supporting-frames, and each consisting 65 of supporting-bars, division-plates, and a strengthening-web connecting said division-plates, leaves or sections mounted on said rocking frame and between said division-plates, and means for rocking said frames, 70 substantially as described.

2. In a grate, the combination with a supporting-frame, of rocking frames mounted in said supporting-frame and each consisting of supporting-bars, division-plates, and a 75 strengthening web or plate connecting said division-plates, and leaves or sections mounted in said rocking frames and between said division-plates, said leaves having their edges resting upon the supporting-bars of said rocking frame and provided with lugs or projections fitting in recesses formed in said division-plates, substantially as described.

3. In a grate, the combination with a rocking frame, said frame consisting of longitudinal parallel supporting-bars, division-plates cast integral with said bars, and provided with recesses, and a strengthening plate or web connecting the lower edges of said division-plates, the end plates of said rocking 90 frame being provided with eccentric lugs or projections forming bearings for said frame, of leaves or sections, adapted to fit in said frame and on said supporting-bars, and provided with lugs or projections on their ends 95 to fit in said recesses in said division-plates, substantially as described.

Signed at New York, in the county of New York and State of New York, this 7th day of August, A. D. 1901.

CHARLES T. COE.
